FLUID CONTROL VALVE

Joseph J. Slomer, Chicago, Ill., assignor to Goodman Manufacturing Company, Chicago, Ill., a corporation of Illinois

Original application January 14, 1944, Serial No. 518,245. Divided and this application March 3, 1945, Serial No. 580,769

4 Claims. (Cl. 303—54)

1

This invention relates to improvements in fluid operated control systems particularly adapted to control the electric circuits of motors used to propel mine locomotives.

The principal objects of my invention are to provide a new and improved form of fluid control valve adapted to positively operate a plurality of devices in a regular sequence or order.

A further object of my invention is to provide a novel form of control valve of a simplified and efficient construction for supplying fluid at pressures increasing or decreasing step by step, arranged to reduce the lap of the valve piston and the mechanical differences of the valve to a minimum and thus reduce the variations in pressure for the same positions of the control handle of the valve as said control handle is turned in an on or an off direction.

This application is a division of application Serial No. 518,245, filed January 14, 1944.

Other objects of my invention will appear from time to time as the following specification proceeds and with reference to the accompanying drawings wherein:

Figure 1 is a fragmentary plan view of a variable pressure control valve constructed in accordance with my invention, with certain parts of the valve broken away and certain other parts shown in horizontal section;

Figure 2 is a fragmentary view in side elevation of the valve shown in Figure 1, with certain parts broken away and certain other parts shown in longitudinal section;

Figure 3 is an end view of the control valve with certain parts thereof shown in transverse section in order to show certain details of the valve;

Figure 4 is a detail transverse sectional view of the valve showing certain details of the manually controllable emergency valve, for releasing fluid from the fluid pressure system;

Figure 5 is a transverse sectional view taken substantially along line 5—5 of Figure 1;

Figures 6 and 7 are enlarged detail sectional views of the variable pressure control valve, showing said control valve in closed and open positions respectively; and

Figure 8 is a detail view of the control valve, showing certain details of the fluid connections thereto.

In the embodiment of my invention illustrated in the drawings, a pressure pipe 39 is provided to supply fluid under pressure to a variable pressure control valve indicated generally by reference character 40 and mounted in a valve block

2

35. A control handle 42 on a vertical shaft 43 is provided to operate said variable pressure control valve in a manner which will hereinafter more clearly appear as this specification proceeds.

5 When said control handle is turned in one direction, fluid under pressure will be delivered from said valve through a pipe 44 at pressures progressively increasing step by step, and when said control handle is turned in an opposite direction, fluid will be released from the opposite end of said valve at pressures progressively decreasing step by step, as will more clearly appear as this specification proceeds.

15 Fluid under pressure is admitted to the variable pressure control valve 40 through a poppet valve 47 mounted in a block or casing 35 for said variable pressure control valve. Said poppet valve is urged into a closed position by fluid entering said valve through the pipe 39 and by a coil spring

20 48. A rocking arm 49 is provided to open said poppet valve. Said rocking arm is pivotally mounted on a vertical shaft 51 at one of its ends and has engagement with the projecting end of a stem 50 of said valve, intermediate its ends.

25 The opposite end of said rocking arm is bifurcated and has a roller 52 mounted between the furcations thereof on a pivotal pin 53 (see Figure 2). Said roller is adapted to engage a notch 54 in a notching cam 55, or any one of a plurality of spaced notches 56, 56 in said notching cam.

30 When said roller is in engagement with the notch 54, said valve will be in an off position. When, however, said roller rides out of said notch and into engagement with the notches 56, 56, effected by pivotal movement of said notching cam, said rocking arm will serve as an index, indexing the positions of the control handle 42 for certain predetermined pressures delivered to the pipe 44, it being understood that since the notches 56, 56 are

35 not as deep as the notch 54, said valve will be in an on position when said roller is in engagement with said notches 56, 56. Said index is herein shown as being formed integrally with a sleeve 57 keyed on the vertical shaft 43 and journaled in 40 the casing 35 for the control valve.

45 As the control handle 42 is turned to an on position, to cause the roller 52 to ride out of the notch 54 and into the first notch 56, or into any one of the succeeding notches 56, 56, fluid under pressure will be admitted to the valve block through the poppet valve 47 to the variable pressure control valve 40 through a passageway 58.

The control valve 40 is of the piston type having a piston 109 movable in a sleeve 110, mounted 55 in the valve casing 35. The variation in pressure

resulting from said piston valve as it is admitting fluid from a lower to a higher pressure and from a higher to a lower pressure, is independent of pressure in an intake pressure line 58 of said valve and is due to the lap of the piston or to mechanical differences only. In order to reduce the lap of the piston and the mechanical differences to a minimum and thus reduce this variation in pressure for the same positions of the control handle as it is turned in an on or an off direction, said piston is provided with three lands 111, 112 and 113, adapted to register with corresponding lands formed in the inner periphery of the sleeve 110, thus providing a multiple lap piston for controlling the delivery of fluid to the pressure line 44. Said piston is drilled along its longitudinal axis from the left-hand end thereof for a portion of its length, and is cross drilled as indicated by reference character 114 at the left-hand end of the land 111, to permit fluid under pressure to pass through the left-hand end of said piston, to and through the pressure line 44. A compression spring 115 extends within the drilled portion of said piston and tends to urge said piston in a direction to the right. Said piston is likewise provided with three lands 118, 119 and 120 adjacent its right-hand end, which control the discharge of fluid to the return. The provision of the multiple lands 111, 112, and 113, and 118, 119 and 120, registering with corresponding lands formed in the inner periphery of the sleeve 110, makes it possible to reduce the lap of the piston so that pressure will be admitted or discharged by said piston with a very slight movement of said piston within the valve sleeve. This will reduce the inaccuracies of said valve due to mechanical differences, and will make the valve sufficiently accurate to insure full and accurate opening and closing of the ports in the distributor valve 41 for the same positions on the control handle 42, when said control handle is being turned in an on or an off direction.

The valve 40 is operated by a pair of spaced gears 123, 123, herein shown as being formed integrally with the control shaft 43. Said gears mesh with racks 124, 124 cut on spaced upper and lower inner ends 125, 125 of a valve operating member 126 (see Figure 5). Said valve operating member is of a substantially C-shaped formation with the racks 124, 124 cut integrally with the upper and lower inner ends thereof, and has a sleeve 127 mounted therein and abutting a closed end 128 thereof (see Figure 2). Said closed end 128 of said valve operating member is slidably mounted on a hollow pilot 129. A hollow piston 130 is mounted on said pilot for movement therewith and extends within said sleeve 127 and is concentrically spaced therefrom. Said hollow piston has an enlarged inner portion which fits snugly within and is secured at its inner end to an inwardly flanged portion of said sleeve 127, as by welding. A compression spring 133 extends within said valve operating member, between the inside of the sleeve 127 and the outside of the hollow piston 130, and is seated at one of its ends in said sleeve and piston. The opposite end of said compression spring abuts and is seated in a seat 134, freely mounted on the inner or right-hand end of the piston 109. The connection between said seat and the valve piston is relatively loose, to avoid binding between said seat and piston and to cause an even pressure to be exerted on said piston by said spring at all times.

The pilot 129 is cross drilled adjacent its outer

or right-hand end and the passageways formed by said cross drilled portion communicate with a passageway 135, leading to a passageway 136, communicating with an annular groove 137 formed in the outer periphery of the valve sleeve 110. Said sleeve is cross drilled from said annular groove into the inside thereof, to permit fluid under pressure to enter said groove 137 through said cross drilled passageways and to pass through the passageways 136 and 135 to and through the hollow pilot 129. Fluid passing through said passageways may thus exert pressure on the inside of the hollow piston 130, to balance the pressure of the spring 133 so the control handle 42 can be operated with a minimum amount of effort and so said control valve will stay in any desired position for which it is set, without being held by the hand. At the same time pressure is exerted on the inside of the hollow piston 130, fluid under pressure passes through the cross drilled passageways 114, to exert pressure on the left-hand end of the valve piston 109 substantially equal to the pressure exerted by the spring 133.

When the valve 47 has been opened by the rocking arm 49 by turning the control handle 42 to an on position, fluid under pressure will enter the passageway 58, which communicates with an annular groove 139 formed in the outer periphery of the valve sleeve 110. Said valve sleeve is cross drilled from said grooved portion 139 to the inner periphery thereof, as is indicated by reference characters 140, 140, to permit fluid to pass from the passageway 58 to the valve piston 109 (see Figures 6 and 7).

When the valve 40 is in the position shown in Figure 6, the spring 133 will be free and there will be a predetermined amount of clearance between the end of said spring and the seat 134. In this position of said valve, the land 111 will close the passage of fluid to the pressure line 44 and there will be no pressure in said pressure line. As the control handle 42 is turned in a direction, which in Figure 2 is a clockwise direction, the valve 47 is first opened to admit fluid to the valve piston 109, as has been mentioned before. The spring 133 at the same time is moved to the left into engagement with the seat 134. Continued turning of said control handle will compress said spring and cause said spring to move the piston 109 to the left until the land 113 is moved out of lap with the corresponding land formed in the valve sleeve 110, as is shown in Figure 7. This will admit fluid within the valve sleeve 110 and will permit fluid to pass by the land 113 into a groove 138 formed in the valve sleeve. From thence fluid will pass in the space between the lands 113 and 112, into a groove 141 formed in said valve sleeve, into the space formed between the lands 112 and 111, into a groove 142 formed within said valve sleeve, through the cross drilled passageways 114, 114 to the hollow center of said valve, and through the hollow center of said valve out through the pressure line 44 to the distributor valve 41. At this time fluid will also be exerted against the left-hand end of said piston, to tend to move said piston to the right against the compression spring 133.

When the pressure exerted against the left-hand end of the piston 109 is greater than the pressure exerted against said piston by the spring 133, said piston will move to the right against said spring. When said piston has been moved

to the right a distance sufficient to move the land 118 out of lap with the inside of the valve sleeve 110, fluid will be discharged through cross drilled passageways 143, 143, through a groove 146 formed within the sleeve 110 in the space between the lands 118 and 119, through a groove 147, formed within the valve sleeve 110 in the space between the lands 119 and 120, through a groove 149 formed in said sleeve, and through passageways drilled from the inner end of said sleeve 10 into said groove, to the hollow chamber formed in the casing 35, and out through a discharge passageway 68 to the low pressure side of the accumulator 15.

When the control handle 42 is turned to the first operating position, the spring 133 is displaced an amount equal to the travel of the operating member 126 minus the clearance between the end of the spring and the valve seat and the clearance between said valve seat and the end of the valve cylinder 110. When said spring has been displaced this amount, fluid under pressure will pass through the hollow piston 109 into the chamber leading to the pressure line 44, at a pressure substantially equal to the force exerted by the spring 133. As pressure in the pressure line 44 tends to increase beyond the force exerted by the spring 133, the valve piston 109 will be moved to the right against the spring 133 by pressure exerted against the left-hand end of said piston, to release fluid from the end of the valve sleeve 110 into the hollow casing 35. As the pressure against the left-hand end of said valve piston is reduced, said spring 133 will move said valve piston to the left a distance sufficient to close the passage of fluid from the passageway 58 to the pressure line 44. If the pressure tends to be reduced below the required value, said spring will move said piston a distance sufficient to admit fluid under pressure past the lands 111, 112 and 113, to the pressure line 44.

It should here be understood that in order to maintain the desired pressure in the pressure line 44 and take care of any leakages of fluid, the piston 109 is continually moving back and forth in the valve sleeve 110, to hold pressure in the line 44 and admit fluid under pressure to said line, or to discharge fluid from the end of the sleeve 110 to the hollow inside of the casing 35 and to the return through the passageway 68.

As the displacement of the spring 133 is increased by turning of the control handle 42 in a clockwise or on direction, the pressure of the fluid entering the pressure line 44 will be correspondingly increased. Thus a definite pressure will be supplied to the pressure line 44 for each notch 56 on the notching cam 55, which pressures progressively increase step by step.

As the control handle 42 is turned in an opposite direction, the displacement of the spring 133 will be decreased for each step on the notching cam 55 and fluid pressure exerted against the left-hand end of the valve piston 109 will move said valve piston to the right. This will permit fluid to be discharged through the return passageway 68, until said valve piston has been balanced and the desired pressure has been established in the pressure line 44 for the corresponding position of the control handle 42.

While I have herein shown and described one form in which my invention may be embodied, it will be understood that the construction thereof and the arrangement of the various parts may be altered without departing from the spirit and scope thereof. Furthermore, I do not wish to be

construed as limiting my invention to the specific embodiment illustrated, excepting as it may be limited in the appended claims.

I claim as my invention:

1. In a variable pressure hydraulic control valve, a valve sleeve, a substantially balanced valve piston slidably movable within said valve sleeve, a spring engaging one end of said piston, means operable to displace said spring in one direction, to move said valve piston to open for the discharge of fluid from one end of said valve sleeve and to permit said valve piston to move in an opposite direction against said spring, effected by fluid pressure on said valve piston, to permit said valve piston to move to a position to permit the discharge of fluid from the opposite end of said valve sleeve, a pressure passageway in said sleeve permitting fluid under pressure to enter said sleeve intermediate the ends thereof, said piston being provided with a plurality of spaced lands throughout its length providing a multiplicity of laps to permit the discharge of fluid under pressure from one end of said sleeve when said piston is moved in one direction by displacement of said spring and to permit the release of fluid from the other end of said sleeve when said piston is moved in an opposite direction by fluid pressure moving said valve piston against said spring, to reduce the lap and amount of movement of said piston for opening or closing said valve.

2. In a variable pressure hydraulic control valve, a valve sleeve, a valve piston slidably movable within said sleeve, a pressure passageway in said sleeve permitting fluid under pressure to enter said sleeve intermediate its ends from the outside thereof, said piston being drilled along its axis from one end thereof for a portion of its length and being cross drilled on one side of said pressure passageway, to permit fluid under pressure to pass through the hollow inside of said piston, said piston also being cross drilled on the opposite side of said passageway to permit the release of fluid from the hollow inside of said piston to the return through said last mentioned cross drills, said piston also having a plurality of spaced lands between said pressure passageway in said sleeve and said pressure cross drills and having a plurality of spaced lands between said release cross drills and the end of said piston, and said sleeve having a plurality of spaced grooves throughout its length disposed between said spaced lands, when said piston is in a closed position, to reduce the lap and amount of movement of said piston for opening or closing said valve.

3. In a variable pressure hydraulic control valve, a valve block, a valve chamber in said block, a valve piston in said valve chamber, a pressure inlet leading into said block and into said valve chamber intermediate the ends thereof, a pressure outlet leading from one end of said valve chamber, a discharge outlet leading from the opposite end of said valve chamber, a control handle, a spring having operative connection with said valve piston and adapted to be displaced by said control handle and urge said piston in a position to permit fluid to pass through said pressure outlet, fluid under pressure passing through said pressure outlet also exerting a pressure on the end of said valve to balance the force exerted on said piston by said spring, said chamber having a plurality of grooves formed therein throughout its length between

said pressure inlet and said pressure and discharge outlets, and said piston being provided with a plurality of lands intermediate said grooves, to permit the discharge of fluid under pressure through said pressure outlet when said piston has been displaced by said spring in one direction, and to permit the release of fluid from the opposite end of said chamber when fluid pressure acting on the end of said piston has displaced said piston against said spring, said grooves and lands being arranged to reduce the lap and amount of movement of said valve piston, when moving to open or close said valve, so said valve will maintain substantially the same pressure at the same position on the control handle, when said valve is turned in an on direction or an off direction.

4. In a variable pressure hydraulic control valve, a valve block, a valve chamber in said block, a valve piston in said valve chamber, a pressure inlet leading into said block and into said valve chamber intermediate the ends thereof, a pressure outlet leading from one end of said valve chamber, a discharge outlet leading from the opposite end of said valve chamber, a control handle, a spring having operative connection with said valve piston and adapted to be displaced by said control handle and urge said piston in a position to permit fluid to pass through said pressure outlet, fluid under pressure passing through said pressure outlet also exerting a pressure on the end of said valve, to balance the force exerted on said piston by said spring, said chamber having a plurality of grooves formed therein throughout its length between said pressure inlet and said pressure and discharge outlets, and said piston being provided with a plurality of lands, intermediate said

grooves, and said piston being drilled for a portion of its length along its longitudinal axis, from the pressure end thereof, and being cross drilled to one side of said pressure inlet to said chamber to permit fluid under pressure to enter the hollow portion of said piston and be discharged through said pressure outlet when said piston has been displaced by said spring in one direction, and being cross drilled to the opposite side of said pressure inlet to permit fluid to be released from the hollow inside of said piston and the end of said chamber opposite from said pressure outlet, when fluid pressure acting on the end of said piston has displaced said piston against said spring, said multiple laps being arranged to reduce the amount of movement of said valve piston to open or close said valve, and thus to reduce the mechanical errors thereof when moving said control handle in a direction to open or close said valve, so said valve will maintain substantially the same pressure at the same position on the control handle, when said valve is turned in an on or an off direction.
